CLAIM

The ornamental design for a lounge chair cover, as shown and described.

DESCRIPTION

FIG. 1 is a left side elevational view of the lounge chair cover of the present invention;

FIG. 2 is a right side elevational view of the lounge chair cover of FIG. 1;

FIG. 3 is a back elevational view of the lounge chair cover of FIG. 1;

FIG. 4 is a front elevational view of the lounge chair cover of FIG. 1;

FIG. 5 is a top plan view of the lounge chair cover of FIG. 1; and,

FIG. 6 is a bottom plan view of the lounge chair cover of FIG. 1.

The cross-hatching represents conventional fabric material and is understood to extend uniformly through out the areas represented.
